MILTON B. REACH, OF CHICOOEE, MASSACHUSETTS, ASSIGNOR TO A. G. SPALDING & BROS. MANF'G. CO., A CORPORATION OF MASSACHUSETTS.

GYMNASIUM-RING.

1,108,003.

Specification of Letters Patent. Patented Aug. 18, 1914.

Application filed October 3, 1913. Serial No. 793,195.

To all whom it may concern:

Be it known that I, MILTON B. REACH, citizen of the United States, residing at Chicopee, Massachusetts, have invented certain new and useful Improvements in Gymnasium-Rings, of which the following is a specification.

My invention is designed to provide a gymnasium ring for use, for instance, as a flying ring or a traveling ring in which, instead of metal as the material to be used, I employ wood which will provide a convenient and comfortable hand-hold from which the hand will not readily slip. In constructing a wooden ring, it is desirable to have the lower portion of the ring of sufficient diameter to afford a proper hand-hold while the upper part of the ring may be of smaller diameter to secure lightness. The ring therefore as constructed by me is of laminated form, consisting of wooden strips bent to ring shape and secured together by any suitable means such as glue, the ring at its lower portion having inserted laminations which are thicker at their central portions and taper toward their ends so that when these pieces are inserted the material of the ring at this portion will be of greater diameter than the cross sectional diameter of the material forming the upper part of the ring.

My invention also includes a wooden ring having a metallic clip or suspension device attached thereto.

In the accompanying drawings, Figure 1 is a side elevation of a ring built in accordance with my invention; and Fig. 2 is a cross sectional view taken vertically.

Gymnasium rings as heretofore made and generally used are of metallic construction and it has been customary to provide them with various kinds of covering. For playground use it is desirable to have a covering from which the hands will not readily slip, and which will resist the action of the weather. As yet so far as I am aware no suitable ring has been devised to meet these conditions, the nearest approach being a wrought iron ring with an aluminum jacket cast thereon. Rings composed of metal, however, soon polish under use and become slippery, and thus afford only an insecure hand-hold. Leather or rubber coverings such as are used in indoor gymnasiums are not practicable for out-door use, as they wear

rapidly, and deteriorate under weather conditions, and under the abuse to which they are subjected on the playground. My ring is of laminations, as indicated at 1. These are so arranged as to retain the full strength of the wood in having the grain continuous in one direction. The ring is round in cross section, and the cross sectional area of the lower part is greater than that of the upper part, this being due to the inserts 2 which, it will be noticed, are considerably thicker at their central portions than at their ends, said inserts being gradually tapered to their ends. By the use of these inserts the lower portion of the ring can be built up to the proper diameter to afford a reliable and comfortable hand-hold, and this can be done without waste of wood or necessitating cutting away parts of the laminated strips, so that an end grain would be exposed. In order to provide a suspending device, various forms may be employed attached to the upper part of the wooden ring, and as one form I show a metallic clamp formed in sections, each section having a curved portion semi-circular in cross section to fit on the ring, and having also an upwardly extending socket portion 3 to receive and hold an enlargement or ball 4 on the loop or clip 5 to which the suspending strap or cord is attached. The two members of the clamp are held together by screws, as shown.

In the manufacture of the ring a long, thin strip of wood, possibly 12 or 13 feet, is used, of the right width and of a thickness proper for making the laminations. This strip is bent continuously around a form, being meanwhile soaked in hot glue, and the inserts for enlarging the diameter are placed at the particular points desired, this being done at the time that the winding is performed. After the ring has been wound up in this way it is clamped and allowed to set, after which it is shaped as shown.

I claim as my invention:—

1. A gymnasium ring comprising an independent strip wound around itself to form a laminated section and means for forming a greater thickness at one point than at another.

2. A gymnasium ring comprising an independent strip wound upon itself with one or more inserts of limited extent held be-

tween the laminations to increase the cross section diameter of the ring at the location of the insert.

3. A gymnasium ring comprising two independent strips wound upon themselves, one forming the inner and the other the outer part of the ring, and an insert of limited extent between said parts.

4. A gymnasium ring comprising more than one section each composed of overlapping laminations and an insert between one or more sections producing a greater thickness at one point than another.

5. In combination with the wooden gym-

nasiun ring, a suspending device of metal 15 composed of two sections each having a curved portion semi-circular in cross section to fit the ring, and each having a socket portion and a loop or clip having an enlargement held within the socket, substantially as 20 described.

In testimony whereof, I affix my signature in presence of two witnesses.

MILTON B. REACH.
